(57) **CLAIM**

An ornamental design for a computer display with graphical user interface, as shown and described.

DESCRIPTION

FIG. 1 is a front view of my new design for a computer display with graphical user interface; and, FIG. 2 is a front view of my new design for a computer display with graphical user interface in an environment of use.

The broken line at the periphery of the figures illustrates the computer display and the remainder of the broken lines illustrate portions of the graphical user interface. None of the broken lines form part of the claimed design.

1 Claim, 2 Drawing Sheets
